Filed July 15, 1968, Ser. No. 12,774

Term of patent 14 years

Int. Cl. D7—01

U.S. Cl. D44—15

FIG.2

FIG.3

FIG.4

FIG. 1 is a top plan view of a bowl showing our new design, the stripping representing irregularly varied tones of brown;

FIG. 2 is a front elevational view;

FIG. 3 is a bottom plan view;

FIG. 4 is a rear elevational view; and

FIG. 5 is a sectional view on line 5—5 of FIG. 1.

We claim:

The ornamental design for a bowl, as shown and described.
